COMBINATION SOUND PRODUCING AND OBJECT EJECTING DEVICE

Filed Nov. 28, 1938

UNITED STATES PATENT OFFICE

2,151,330

COMBINATION SOUND PRODUCING AND
OBJECT EJECTING DEVICEHarold N. Prensky, Forest Hills, and Eugene
Grieshaber, Springfield Gardens, N. Y.

Application November 28, 1938, Serial No. 242,656

9 Claims. (Cl. 46—124)

This invention relates to devices for producing sounds of intermittent and varying duration and for ejecting an object immediately subsequent to the period of the sound of longest duration. The 5 nature of the invention lends itself to be employed in toys in which the sound produced simulates, for instance, the cluck and cackle of a hen and the objects released, simulated eggs, the latter being released subsequent to the clucking sounds and during the cackling sound substantially as occurs in nature.

It is, therefore, an object of this invention to provide a toy of the above character which is attractive, simple of construction, and quite easy 15 to assemble and operate.

The invention further resides in the structural features of the sound producing means and in the co-related means for releasing and dropping the mentioned object.

20 With the foregoing and many other features, objects, and advantages in mind, the invention resides in the combination and arrangement such as illustrated in the accompanying drawing in which a preferred embodiment of the invention is shown. The following specification, based on 25 said drawing, describes in detail the features of the invention.

In the drawing:

Fig. 1 is a side view, partly broken away, of a 30 toy incorporating the features of the invention.

Fig. 2 is an end sectional view thereof as taken substantially on the line 2—2 of Fig. 1.

Fig. 3 is a plan sectional view of the mechanism used in the toy.

Fig. 4 is an enlarged fragmentary plan sectional view of a portion of the mechanism.

In that embodiment of the invention which is illustrated, the toy contemplated comprises a preferably sheet metal housing 5 designed and colored to simulate a hen setting in a basket or the like. The housing, in this instance, is formed of two parts for ease of assembly therein of the sound-producing and object-releasing mechanism generally designated 6.

45 The sound-producing portion of the mechanism will be first described. It comprises a tubular member 7 having an end diaphragm 8 on which is mounted a reed 9. Thus vibration of the reed will cause vibration of the diaphragm, the sound being amplified in the tubular member which acts as a sound chamber.

Within the tubular member there is preferably mounted a metal frame comprising the legs 10 and the bridge portion 11. The mounting means 55 may comprise the lugs 12 struck from the frame to bear on one edge of the tube 7, and outwardly and rearwardly bent lugs 13 engaging an intermediate portion of said tube. These latter lugs 60 may be somewhat extended to have connection

with the toy housing 5 to serve as means for anchoring the mechanism 6 within said housing.

The legs 10 of the frame are apertured for the shaft portion 14 of a crank handle 15, the latter projecting outside of the toy housing 5. In the 5 present instance at least the shaft portion is of polygonal cross-section to serve as keying means for the sleeve 16 and the gear pinion 17 mounted thereon. In this manner the sleeve 16 may slide on the shaft and turn therewith. 10

The sleeve 16 serves to mount the two plate members 18 and 19. The former is formed with two opposed serrated peripheral edges 20 of relatively short extent and the latter, with a continuous peripheral serrated edge 21 of substantially 15 greater extent with respect to the edges 20. These serrated edges are related to the reed 9 in a manner to vibrate said reed upon turning of the crank handle 15.

Between the sleeve 16 and the pinion 17 are 20 disposed a cylindrical cam 22 having an edge cam face 23, and a sleeve 24 carrying an arm 24^a having engagement with said cam face. Both the cam 22 and the sleeve 24 are formed with round central bores so as not to be affected by 25 the rotation of the shaft 14. A compression spring 25 is strung on the shaft between one of the frame legs 10 and the outer end of the sleeve 16 to normally maintain in abutment the sleeves 16 and 24, the cam 22 and the pinion 17. 30

Upon the cam 22 is preferably carried a gear wheel 26 having engagement with a pinion 27, the latter being integral with or affixed to a gear 28 in mesh with the mentioned pinion 17. The pinion 27 and gear 28 are mounted for rotation 35 on or with the stud shaft 29 carried by the frame leg 10 and a bracket 30 carried thereby.

From the above it is evident that turning of the crank handle 15 will cause the plates 18 and 19 and the gear 17 to turn at the same rate of speed 40 as said handle and since the arm 24^a is disposed on the low part of the cam face 23, the plate 18 will have engagement with the reed 9. Thus the opposed edges 20 of said plate will alternately vibrate said reed to produce an intermittent sound 45 simulating the clucking of a hen.

As the rotation of the handle progresses, the mentioned gearing causes slower rotation of the cam 22 and the cam face gradually urges the sleeves 24 and 16 endwise against the compression 50 of the spring 25. In the present showing the relation of speed of the shaft and cam are approximately five to one and thus the plate 18 will have five revolutions to each revolution of the cam. Hence approximately ten "clucks" are produced 55 by the serrated edges 20 intermittently vibrating the reed.

As the high-point of the cam becomes effective on the arm 24^a, the plate 18 loses engagement with the reed and the plate 19 comes into engage- 60

ment therewith and a considerably longer sound simulating a long drawn-out "cackle" is produced, then as the arm 24^a rides off the high-point of the cam, the spring 25 acts to restore all the parts 5 to their initial endwise position so the cycle of sounds may be repeated. It will be noted from the drawing the high part of the cam may have increased pitch with respect to the normal pitch of said cam to cause a more rapid traverse of the 10 plates 18 and 19 as they exchange engagement with the reed.

The article releasing portion of the mechanism comprises a substantially vertically disposed stacking hopper 31 having an upper opening 15 accessible through the housing 5 so that articles such as the simulated eggs 32 may be dropped therein to be supported on the horizontally disposed lug 33 formed on an extension of the arm 24^a, the latter protruding through a slot 34 20 formed in the bridge 11. Below said lug is disposed a chute 35 directed towards an opening 36 in the toy housing 5.

From the above it is apparent that as the handle is turned and the arm 24^a moves endwise by 25 the cam, the lug 33 will gradually move from beneath the lowermost object 32 so that said object will fall upon the horizontal portion 31 of the chute. Then simultaneously with the last portion of the "cackle", i. e., when the arm rides 30 off the high point of the cam, the extension of the arm 24^a, with the force of the spring 25, will eject the object 32 down the chute 35 and through the opening 36 in the housing.

The foregoing is descriptive of a preferred form 35 of the invention and it is evident that an attractive, amusing, and quite simple device has been disclosed. It is also evident that changes within the spirit and scope of the invention may be made by those skilled in the art.

40 What we claim as new and desire to secure by Letters Patent, is:

1. A combined sound producing and object 45 ejecting device comprising a manually rotatable shaft, a pair of plates on said shaft, one having relatively small serrated peripheral portions and the other a relatively greater serrated peripheral portion, vibration means including a reed, means operable upon rotation of said shaft for first contacting one of said plates with said reed and then 50 the other, a stack of objects, and means connected with said last mentioned means for ejecting from said stack the lowermost object immediately subsequent to the contact between the reed and the plate having the greater serrated peripheral portion.

55 2. A combined sound producing and object ejecting device comprising a manually rotatable shaft, sound producing means comprising vibration means having a reed and a pair of plates on 60 said shaft and rotatable therewith, means operable by said shaft for moving said plates into alternate engagement with said reed, a stack of objects, and means connected with said last mentioned means for ejecting from said stack the 65 lowermost object immediately subsequent to the engagement between the reed and one of said plates.

3. A combined sound producing and object 70 ejecting device comprising a manually rotatable shaft, sound producing means comprising vibration means having a reed and a pair of plates

on said shaft and rotatable therewith, one of said plates having serrated peripheral portions of relatively small extent, the other having a serrated peripheral portion of relatively greater extent, means operable by said shaft for moving said plates into alternate engagement with said reed, a stack of objects, and means connected with said last mentioned means for ejecting from said stack the lowermost object immediately subsequent to the engagement between the reed and the plate having the greater peripheral serrations.

4. A combined sound producing and object 15 ejecting device comprising a manually rotatable shaft, sound producing means comprising vibration means having a reed and at least one plate on said shaft and rotatable therewith, means operable by said shaft for axially moving said plate into and out of engagement with said reed, a stack of objects, and means connected with 20 said last mentioned means for ejecting from said stack the lowermost object immediately subsequent to the engagement between the reed and the plate.

5. A sound producing device comprising a vibration member having a reed, a manually operable shaft, a pair of plates rotatable with said shaft and slidably thereon, and means operable by said shaft for alternately engaging the peripheries of said plates with said reed for vibrating said reed during rotation of said shaft, one of said plates having serrated peripheral portions of lesser extent than the serrated peripheral portion of the other.

6. A sound producing device comprising a vibration member having a reed, a manually operable shaft, a pair of plates rotatable with said shaft and slidably thereon, and means operable by said shaft for alternately engaging the peripheries of said plates with said reed for vibrating said reed during rotation of said shaft, said means comprising a cam mounted for rotation on said shaft, gear means between said shaft and said cam for rotating said cam at a lower rate of speed than the shaft, and means movable by the cam for sliding said plates endwise along said shaft.

7. In a device of the character described, a sound producing unit having a vibrating reed, and a pair of peripherally serrated plates movable into alternate engagement with said reed for vibration thereof.

8. In a device of the character described, a sound producing unit having a vibrating reed, and a pair of peripherally serrated plates movable into alternate engagement with said reed for vibration thereof, one of said plates having its serrated portions of lesser extent than the other.

9. In a device of the character described, a sound producing unit having a vibrating reed, a plate having serrated peripheral portion of small extent normally in engagement with said reed for vibration thereof, a second plate having a serrated peripheral portion of greater extent, means for moving the mentioned plates to disengage the first plate and engage the second plate with said reed, and means for restoring said plates to the mentioned normal condition.
